UNITED STATES PATENT OFFICE.

FERDINAND KRONENBERGER, OF HASTINGS, NEW YORK, ASSIGNOR TO FREDERIC B. CLARK, OF ENGLEWOOD, NEW JERSEY.

EGG-CARRIER.

1,208,800.

Specification of Letters Patent. Patented Dec. 19, 1916.

Application filed August 9, 1913. Serial No. 783,864.

To all whom it may concern:

Be it known that I, FERDINAND KRONENBERGER, a citizen of the United States, residing at Hastings, county of Oswego, and 5 State of New York, have invented a certain new and useful Egg-Carrier, of which the following is a specification.

This invention is an article carrier, the same being for the shipment of eggs, fruit, 10 vegetables and other objects without breakage or injury.

The object in view is the production of a simple contrivance which will hold the objects so securely in position that they will 15 not be broken or injured by the shock or jar to which they are exposed during shipment, particularly by rough handling.

The carrier is a substitute for the ordinary cell case, and a number of said carriers are adapted to be stacked or piled with the articles within an ordinary packing case; but by reason of the safety and security accorded to the articles, the carrier or carriers are useful in small cartons or 25 packages for the shipment by parcel post of perishable objects from the producer to the consumer.

The carrier of the present invention embodies a member provided with rows of 30 pockets and having crossing stays integral with said member, said stays constituting in effect a cell case with the article receiving pockets produced in a sheet integral with the stays.

It is preferred to produce the article carrier from a sheet of paper, or other material suitable for the purpose, and to this end the paper is slotted and creased at certain lines and is slotted at portions intermediate the slotted and creased parts thereof, as a result of which the sheet is adapted to be folded in two directions along the creased portions so as to produce stays which cross or intersect each other and are integral with 45 the sheet. The slotted parts of the sheet are adapted, when the carrier is in use, to be deflected by articles so as to form pockets to receive such articles, and the carriers and objects are confined under pressure so that 50 the articles will be held securely and yieldably to the end that no movement or displacement of such articles can take place. When my carriers are used in an ordinary packing case, they are assembled in pairs,

with separators between adjacent pairs, the two carriers of each pair being reversed with respect to each other so as to bring the slotted parts in facing relation and the pockets formed by said slotted parts into register, whereby the two carriers forming each pair 60 will operate to confine the rows of objects firmly in position. It is not desired, however, to restrict the invention to a carrier composed of sheets of paper slotted and creased as described, for the reason that 65 said carrier may be composed of molded or pressed pulp characterized by the employment of a sheet with integral pockets and by the use of crossing stays which are integral with the sheet in the intervals between the pockets thereof.

In the drawings, Figure 1 is a vertical section through a packing case illustrating a stack or pile of carriers installed therein for supporting layers of eggs in an non-breakable condition. Fig. 2 is a plan view illustrating one form of the carrier. Fig. 3 is a plan view showing another form of the carrier. Fig. 4 is a plan view of a blank from which the carrier of Fig. 3 is produced. Fig. 5 is a vertical section showing the manner of deflecting the yieldable fingers in the carrier of Figs. 3 and 4.

The carrier shown in Figs. 1 and 2 of the drawings embodies a member A provided 85 with pockets B and intersecting stays C, D. The pockets are arranged in rows, each pocket being provided with a series of slits b radiating from a common center and extending nearly to the rim of the pocket, said 90 slits forming yieldable members adapted to be deflected by the pressure of the article contained within the pocket. The stays C, D are integral with the member A, said stays C extending transversely of the member, whereas stays D extend longitudinally 95 of the member. The stays C D cross or intersect each other and they are positioned in the intervals between the pockets of the rows, whereby the stays operate to reinforce 100 the member A so as to preclude bending or deflection thereof under the pressure of the articles packed within the case. In Figs. 1 and 2 each carrier A is composed of a single piece of material, said carrier being molded 105 or pressed from pulp or other suitable fibrous material. The slits b in the pockets may be omitted, but it is preferred to provide the

slits in the bottom of each pocket in order to produce the yieldable members.

The carriers A are employed in pairs, one carrier being inverted with respect to the other carrier, and the two carriers of each pair being assembled in facing relation so that the pockets will register. Thus, in Fig. 1 a carrier A is placed upon the bottom e of a packing case E; a row of objects, such as eggs, are then placed in the pockets of the carrier; a second carrier A is then introduced into the case, said second carrier being reversed or inverted with respect to the first carrier and the pockets of the second carrier receive the upper portions of the eggs or other objects. A sheet or layer of material F is now placed upon the second carrier, after which a third carrier A is deposited upon the separating sheet F. After another layer of eggs shall have been deposited upon the third carrier, a fourth carrier A, occupying an inverted position with respect to the third carrier, is now introduced into the case so as to receive the objects, and thereafter a second separating layer F is deposited upon the fourth carrier. These operations are repeated by introducing the carriers, separators, and the layers of eggs until the packing case E is substantially filled, the objects being held or confined between two carriers composing a pair, and said objects being retained in the pockets of the adjacent carriers. During the operation of packing the case pressure is applied to the carriers so as to force the objects into the pockets of said carriers under sufficient pressure to bend or deflect the yieldable fingers formed by the slotted pockets, and thus the objects are securely retained under pressure in the pockets of the carriers so that the objects cannot work loose and come into contact with each other. The objects packed between and within the carriers are so securely retained that they cannot become broken or injured during transportation. The articles can be easily and quickly packed in the case by placing them in the pockets, and as the pockets are provided with yieldable members it is evident that articles of different sizes can be packed and securely held without breaking or injuring them.

A preferred form of construction is illustrated in Figs. 3, 4 and 5 of the drawings, wherein the egg carrier is produced from a blank of paper or other fibrous material suitable for the purpose, the blank being shown more particularly in Fig. 4. The blank G is cut or slotted, as at g, thus leaving solid portions h. In these solid portions are slits h', the slits of each group radiating from a common center and producing yieldable members which are adapted to be deflected so as to result in a pocket H, shown in Figs. 3 and 5. The portions i between the slotted portions h are scored or

creased at j $\frac{1}{2}$, the scoring k running at right angles to the scoring j. The blank is cut, slotted and scored in suitable dies at one or more operations, and the flat blanks G thus produced are adapted to be stacked or piled 70 for convenient transportation. When it is desired to use a carrier the blank is removed from the package or pile, and the operator proceeds to bend or fold the blank in the following manner: It is folded longitudinally in one direction along the score lines j so as to produce a series of stays J running in one direction with respect to the carrier; thereafter the blank is folded in another direction and along the score lines k, thus producing other stays K which intersect with the stays J for the reason that the stays K run at right angles to the stays J. The operation of folding the blank in two directions so as to result in the stays J K brings 80 the slotted portions h closer together, as shown in Fig. 3, and as a result of this manipulation of the blank G, shown in Fig. 4, there is produced a carrier of the form shown in Fig. 3, wherein the slotted pockets 90 H in the sheet or member are integral with stays J K which extend crosswise of the carrier and intersect with each other, substantially as shown in Figs. 3 and 5. After a number of the carriers have been folded, 95 they are assembled in a packing case in the manner shown in Fig. 1, that is to say, two carriers are employed in connection with each layer of articles, the carriers constituting each pair being reversed in position so 100 that the pockets will oppose each other and register with each other, whereby the objects will be deposited in the pockets of the bottom member and be received in the pockets of the top member. The two carriers of 105 the pair having been properly assembled with the articles between them, a separating layer F is placed upon the uppermost member, and pressure is applied so as to force the articles into the pockets of the two members, which pressure deflects the yieldable fingers formed by the slotted portions h so 110 that the articles will be held securely by the yieldable fingers of the opposing members 115 composing the pair of carriers.

Having thus fully described the invention, what I claim as new, and desire to secure by Letters Patent is:—

1. An article carrier embodying a plurality of coöperating members assembled for fixedly retaining in position the articles to be packed, each member comprising a sheet or web provided with pressure-transmitting stays, said stays being integral with the sheet or web and extending in crossing relation to each other, and said stays bounding definite areas of the sheet or web, which definite areas of the sheet or web are slotted intermediate the stays and said slotted portions producing tongues which are positioned 130

- for frictional contact with articles placed between the members and operating to retain said articles under pressure.
2. An article carrier of the class described embodying a sheet or web provided with integral pressure-transmitting stays, said stays extending from one surface of the sheet or web and certain of said stays extending at a right angle to the remaining stays so as to form cells located at one side of the sheet or web, certain parts of the sheet or web being bounded by the cell-forming stays and said certain parts being cut to produce resilient members which are yieldable to the pressure of articles occupying the cells so as to be deflected from the plane of the sheet or web.
3. An article carrier of the class described embodying a sheet or web provided with rows of slitted portions, and pressure-transmitting stays integral with said sheet or web and extending from one surface thereof, said stays being joined to the sheet or web in the intervals between the slitted portions thereof.
4. An article carrier embodying a plurality of members assembled for fixedly retaining in position the articles to be packed, each member comprising a sheet or web provided with two rows of integral stays extending in one direction from a surface of said sheet, the stays of one row being at right angles to the stays of the other row and bounding definite areas of the sheet so as to produce a series of cells, said sheet or web being slitted in the spaces bounded by the stays and producing resilient tongues positioned for frictional contact with the articles adapted to be held between the first named members, said definite areas of the sheet bounded by the stays being characterized by a certain stiffness or rigidity as compared with the yieldable tongues so that the margins of the web at the slitted portions thereof operate to apply pressure upon the articles the resistance of which deflects said tongues from the plane of the sheet or web.
5. An article carrier of the class described comprising a slotted blank of sheet material, said sheet material being cut or slit to produce yieldable members and said blank being foldable in two directions on lines intermediate said slotted portions, said folded portions of the sheet material producing pressure-transmitting stays integral with the sheet and bounding the spaces formed with the slotted portions of said sheet.
6. A blank for a one-piece article carrier of the class described comprising a sheet of material scored in two directions and provided in the spaces intervening said score lines with slits, said sheet material being foldable on the score lines to produce pressure-transmitting stays integral with the sheet, which stays bound the spaces provided with the slits and said slits being yieldable so as to be deflected from the plane of the sheet.
7. A blank for a one-piece article carrier of the class described comprising a sheet of material slotted and slitted at intervals and provided intermediate the slotted portions with score lines extending in two directions, said blank being foldable on the score lines to produce two series of pressure-transmitting stays integral with the sheet in the intervals between the slotted portions thereof.
8. An article carrier comprising a sheet or web provided with integral stays which are positioned in crossing relation and extend in one direction from a surface of the sheet, said sheet being provided in each space bounded by the stays with groups of slits which produce yieldable tongues adapted for frictional contact with the articles whereby said articles are held under pressure by said tongues and by contact therewith of the slotted marginal portions of the sheet.

In testimony whereof I have signed my name to this specification in the presence of two subscribing witnesses.
